UNITED STATES PATENT OFFICE

GEORGE ADOLPH STEINER, OF SALT LAKE CITY, UTAH, ASSIGNOR TO STEINER SALES COMPANY, OF SALT LAKE CITY, UTAH, A CORPORATION OF UTAH

GARMENT

Application filed January 22, 1932. Serial No. 588,138.

My invention relates to outer garments or gowns and particularly to those of the smock type that are intended to be worn in offices, stores and industries of various kinds in place of the ordinary street clothes or dresses, which generally will be removed and this garment substituted therefor, or the garment may be worn over the street dress if preferred; the object being to provide a loose, comfortable short sleeve garment which will allow the free use of the limbs of the wearer, be cool and comfortable in warm weather or in certain industries where the temperature is maintained at a comparatively high degree and, at the same time, completely cover and protect the underclothing or the dress over which the garment may be worn.

The primary object of my invention is to provide a garment having a belt with provision for drawing it snugly around the person of the wearer under the front of the garment where the belt at that point will be concealed when the garment is buttoned, or the belt may be passed around the waist of the wearer on the outside of the garment where it will be visible as usual in belted garments.

A further object is to provide a garment having a belt arranged in such a way that the garment can be laundered without danger of the ends of the belt becoming tangled.

Other objects of the invention will appear from the following detailed description.

The invention consists generally in various constructions and combinations, all as hereinafter described and particularly pointed out in the claim.

In the accompanying drawings forming part of this specification,

Figure 1 is a view of the back of the garment showing the position of the belt thereon and the provision for passing the ends through openings provided in the back panel;

Figure 2 is a front view of the garment showing how the ends of the belt after being passed through the openings in the back may be fastened together and be concealed when the garment is buttoned at the front;

Figure 3 is a view corresponding to Figure

1 showing the ends of the belt withdrawn from the openings in the back;

Figure 4 is a view corresponding to Figure 2 showing the appearance of the garment when it is first buttoned and when the ends of the belt are drawn around at the front and fastened together on the outside of the garment.

In the drawings, 2 represents the back center panel of the garment, and 3 and 4 the side panels stitched to the back at 5 in any preferred manner and having the usual pockets 6, the short sleeves 7 and a suitable collar 8. The side panel 4 is provided with buttonholes 9 to receive the usual buttons 10 provided on the edge of the panel 3.

This makes a garment of the usual gown or smock type and generally is worn next to the undergarments, the street dress or gown being removed. These garments are made of washable material and, being worn in offices, stores, shops and factories where the garments will become easily soiled, laundering is frequently required.

Gowns of this type are usually provided with two styles of belts and linen supply houses, to avoid changing the belt, should keep two styles of gowns in stock, one with the belt sewed only across the outside of the back and the other with a full belt that can be passed around the entire outside of the gown. Often patrons will use one style of gown for a time and then request that a gown with another arrangement of belt be furnished, and this of course involves changing the belt or keeping a supply of both styles on hand, thereby adding to the trouble and expense of the linen companies.

To avoid this objection and inconvenience incident to the garment as usually made, I propose to provide a belt 15, attached to the back panel at 11, and buttons 12 may be placed at this point for ornamentation, and preferably in the seam between the side and back panels I provide openings 13 of suitable size to receive the ends of the belt 15 so that when these ends are inserted through the openings only the middle portion of the belt will be visible at the back and the loose ends may be brought around the person of the wearer un-

der the front of the gown and fastened together at the front, as indicated in Figure 2, by suitable means such as a pin 14. A buckle (not shown) may of course be provided at 5 this point, or one end may have a series of buttonholes to receive a button fastened to the other end. These fastening means being obvious are not shown. For convenience of laundering, however, I may prefer to omit 10 any fastening means for the ends of the belt and allow the wearer to secure these ends together as by means of a pin.

When the ends are fastened together, as 15 shown in Figure 2, the panels of the garment are drawn together and buttoned and, while the waist portion of the garment will be drawn in snugly by the belt, there will be no portion of the belt visible at the front, this portion of the belt being entirely covered by 20 the garment. At the same time the back and side panels will be drawn in around the waist of the wearer.

Instead of passing the ends of the belt 25 through the openings between the back and side panels, I may pass the belt around the outside of the garment in the usual way as shown in Figure 4, thus exposing the entire belt to view, and the lapping ends of the belt may be pinned together, as shown, or may be 30 connected by any suitable means for this purpose.

I am thus able by arranging the belt in this way to adapt a garment for use either with 35 the front of the belt on the inside, concealed at the front and exposed in the back, or on the outside and worn in the usual way; thus one type of garment will be sufficient to supply the patrons of the linen company, some of whom may desire the belt on the inside 40 concealed at the front and others the belt on the outside and visible in front.

I have shown this idea applied to a washable gown for the purpose of adapting it for 45 use either with an entirely visible belt or one visible only in the back, but it will be understood that the same idea may be incorporated in other styles of garments which it may be desired to use at times with the belt invisible at the front or with one that is visible; hence, 50 I do not wish to be confined to the use of this idea in the particular garment illustrated and described herein.

From the foregoing description, it will be 55 understood that the belt may be worn either across the outside of the back of the garment or around the entire outside of the gown. If the patron wishes to wear the garment so that the belt will only show across the back, she will pass the ends through the two openings 60 in the side panels and fasten them together at the front, and when the gown is buttoned the belt will be on the inside in the front and on the outside at the back. If the wearer wishes to use the garment with the 65 entire belt showing it is only necessary to

pull the ends out of the openings in the sides of the garment, pin these ends together at the front after buttoning the side panels together. With this manner of use the belt 70 will be visible entirely around the garment.

When the garment is being laundered, if the ends of the belt are thrust into the openings in the sides they will not tangle in the wash as these ends will be on the inside of the gown and be protected thereby during 75 the washing operation.

I claim as my invention:

A washable garment of the type described, 80 having front and rear panels of washable material, seams formed by lines of stitching connecting the panels, and each having an opening therein, and a belt also of washable material having loose ends and fastened substantially at the middle thereof to the back panel, the loose ends of said belt being adapted to be selectively passed through the openings in said seams and connected together 85 at the front of the wearer, concealed beneath the front of the garment, or to be drawn out of said openings and secured together at the front of the garment on the outside thereof, for the purpose specified.

In witness whereof, I have hereunto set my hand this twelfth day of January, 1932.

GEORGE ADOLPH STEINER.
